METHOD AND MEANS OF PRODUCING
POWER

Edwin Jacobsen, Altadena, Calif.

Application September 24, 1945, Serial No. 618,212

5 Claims. (Cl. 123—197)

1

This invention relates to internal combustion engines, and particularly pertains to a method and means of producing power.

The standard type of reciprocating internal combustion engine is designed of necessity on the principle that the power stroke begins in the interval when the crank throw of the engine piston passes over top dead-center. It is obvious that when combustion takes place within the cylinder with the piston on top dead-center the moment of torque force around the crankshaft axis will be zero, and thus the explosive force incident to combustion will not be converted into tangential torque force around the axis of the crankshaft. This condition results in a definite power loss aside from the fact that considerable strain and wear is set up in the engine structure. Various attempts have been made to correct this fault in reciprocal engine design, such as is disclosed in my U. S. Letters Patent No. 2,314,789, issued to me March 23, 1943, and in my co-pending application entitled "Internal combustion engines," Serial No. 527,977, filed by me in the United States Patent Office March 24, 1944. In my solution of the problem, as disclosed in the aforementioned patent and application, I have provided a structure in which the piston and crank throw therefor will not be concurrently on top dead-center, but that the crank throw will be several degrees beyond its dead-center position when the piston is at its uppermost end of the stroke. Such an arrangement prevents power loss at the time the piston is at its uppermost position and is starting its firing stroke. This arrangement also tends to insure that a maximum proportion of the power cycle of the engine will be occupied in transmitting the explosive power into tangential force. It is desirable to provide an internal combustion engine having all of the foregoing advantages, and which insures that the crankshaft will be so balanced as to maintain the complete cycle of engine operation in the first harmonic phase without setting up vibrations and disturbances in the second harmonic phase, thus insuring that a high power reciprocating engine will function to produce a maximum amount of power with a minimum amount of vibration, and thus reducing the amount of stress and wear set up in the engine. It is the principal object of the present invention, therefor, to provide an internal combustion engine of the reciprocating type where one-hundred percent of the total force acting on the piston is converted to tangential force, or useful work, during the combustion portion of the power

2

stroke, and which further insures that any tendency for the piston and crank units to concurrently reach a zero moment will be obviated by means which prevent a rigid and positive dead-center action to occur either in the crankshaft or with relation to the reciprocating piston.

The present invention contemplates the provision of an engine having a cylinder within which a piston reciprocates, which engine is provided with a crankshaft operatively connected to the piston, and a power output shaft in driving connection with a crankshaft, said crankshaft being suitably counterbalanced with the rotating portion of the reciprocating forces and being mounted to move bodily with relation to the power output shaft and in a direction opposite to the piston movement, said movement providing means for complete balance of the reciprocating parts in the first harmonic phase, and to insure the transmittal of maximum driving torque from the piston to the power output shaft.

The invention is illustrated by way of example in the accompanying drawings in which:

Figure 1 is a view in side elevation showing a complete engine with which the present invention is concerned.

Fig. 2 is an enlarged view in transverse section through the engine as seen on the line 2—2 of Fig. 1 and shows the crankshaft construction and mounting, the counterbalance therefor, and the driving connection with the power output shaft.

Fig. 3 is a fragmentary view in section and elevation as seen on the line 3—3 of Fig. 2 and shows the construction of one complete cylinder unit including the piston, crankshaft, and the crankshaft mounting.

Fig. 4 is a view in diagram showing the piston of the engine on absolute dead-center and indicating the relationship of the crankshaft and the power output shaft at that instant.

Fig. 5 is a view similar to Fig. 4 showing the piston, the crankshaft, and its mounting directly after firing. This view also shows the manner in which the crankshaft support adapts itself to the initial firing impulse prior to the time it takes for the power stroke to be transmitted to torque force around the axis of the crankshaft.

Fig. 6 is a view similar to Fig. 5 but shows the crankshaft after the crank throw has passed over dead-center and the yieldable crank support has had time to move back to a condition of equilibrium.

Fig. 7 is a view similar to the preceding view but it shows the piston and the crankshaft on

bottom dead-center, and thus 180° beyond its position when at top dead-center.

Fig. 8 is a graph showing the engine performance of an engine at full throttle selected for the purpose of demonstrating the present invention.

Fig. 9 is a view in diagram illustrating the relative movement of the axes of the crankshaft during one revolution of the crankshaft.

Referring more particularly to the drawing, 10 indicates a cylinder block which is mounted upon a crankcase 11. The cylinder block carries a desired number of cylinders 12 within each of which a piston 13 reciprocates. The cylinder heads include an intake port 14 and an exhaust port 15. The intake port is here shown as connected with a carburetor and heater unit 16. The intake gas is controlled by the usual tappet valve 17 actuated by a timing shaft 18 having timing cams 19 thereon. The piston 13 is provided with a connecting rod 20 pivotally attached to the piston by a wrist-pin 21 and attached to the crank-pin 22 of a crankshaft 23. By reference to Fig. 3 of the drawing, it will be seen that the crankshafts are individual units, one provided for each piston. They are also mounted for individual movement both in rotation around their axes and also when they and their axes move bodily in the plane of the longitudinal axis of the cylinder 13. Each of the crankshafts 23 have crank-arms 24 between which the crank-pin 22 is mounted. The crankshaft 23 is a composite shaft structure having sections 23^a which are concentric with the rotating axis of the engine, and sections 23^b which are eccentric to the rotating axis of the engine. The eccentric sections 23^b are journaled in bearings 25 which are carried at the upper ends of vertical oscillating arms 26. As shown in Fig. 3 of the drawings the eccentric crankshaft sections 23^b are formed directly with the outer faces of the crank arms 24. Thus, the crank-arms 24 and the connecting crank-pin 22 gyrate around the eccentric axes of the crankshaft sections 23^b and between the vertical arms 26. The lower ends of the arms 26 are formed with bearing members 27 which receive bearing bushings 28. Disposed at opposite ends of the bearings 27 are supporting journals longitudinally aligned with the axes of the bearings 23 to receive a pivot shaft 30, around the axis of which the vertical arms 26 oscillate, as will be hereinafter described. The journals 29 are tied together by an intermediate web 31 and are fastened by cap screws 32 to the upper face of a resilient accumulator plate 33. The accumulator plate 33 is of a width substantially agreeing with the overall length of the pivot shaft 30. By reference to Fig. 2 it will be seen that the plate 33 is substantially rectangular, and that in a plane normal to the axis of the pivot shaft 30 its lower face tapers upwardly and outwardly from the point of mounting of the journals 29 to the edge thereof. This point of mounting is substantially midway between the edges of the plate 33. The plate 33 has been selected to have a desired resilience so that under conditions to be hereinafter explained it will deflect downwardly under the influence of force applied from the crankshaft through the arms 26. Mounted over the outer edges of the accumulator plate 33, and which edges are parallel to the axis of the shaft 30 are rocker bars 34. These bars are slotted to receive an edge of the plate, after which they are secured in position by screws 35. Complementary socket clamps 36 partially embrace the rocker bars 34 and are held in position by bolts 37 which are fastened through

flanges 38 extending inwardly from the walls of the crank-case. The inner edges of the socket clamps 36 are relieved, as indicated at 39, to permit flexure of the accumulator plate 33 as the rocker bars 34 rotate on their axes. The clamping sockets 36 are braced rigidly by a transverse brace member 40 which is disposed below the clamps 36 and through which the bolts 37 extend. This brace member is formed with central openings 40' to accommodate the heads of the cap screws 32 when the accumulator plate 33 is deflected. A drain pan 41 is secured to the bottom of the crank-case and houses the previously described structure.

The individual crankshaft units are intended to drive a common output power shaft 42. This shaft is mounted in suitable bearings 43 formed within the crank-case 11. The power output shaft 42 is fitted with a plurality of gears 44, one of the gears being provided for each of the crank units. In mesh with each of the gears 44 is a gear 45. The gears 45 are secured to bolting flanges formed integral with the concentric sections 23^a of the crankshaft. The engine is designed to permit separate migratory movement of the axes of the concentric crankshaft section 23^a and the eccentric crank section 23^b. As previously explained, the eccentric crankshaft section 23^b is mounted upon the upper end of vertical crank arms 26 which oscillate around the horizontal axis of the shaft 30. The concentric crankshaft sections 23^a of each crankshaft unit are mounted upon radius arms 46. These arms are mounted at one end upon the power output shaft 42 around the axis of which they pivot. The free ends of these arms are mounted upon the concentric sections 23^a of the crankshaft, so that as the arms 46 oscillate the crankshaft sections 23^a will swing on an arc concentric with the axis of the power output shaft 42. This will insure that the gears 44 and 45 will remain in constant mesh at all times. It is intended that the axes of the crankshaft sections 23^a shall travel along an arcuate path which is tangent to the vertical center of a complementary engine cylinder 12, and that when the concentric sections 23^a of a crankshaft unit are in the horizontal plane with the axis of the power output shaft 42 the engine piston 13 will be on top dead-center. At such a time the axes of the eccentric shaft sections 23^b will be in substantially the same vertical plane as the axes of the concentric crankshaft sections 23^a. Thus, at this particular time the axis of the pivot shaft 30 and the eccentric crankshaft sections 23^b and the axes of the concentric crankshaft sections 23^a of a particular unit will lie in substantially the same vertical plane as the vertical axis of a complementary engine cylinder, while the axes of the concentric crankshaft sections 23^a and the power output shaft 42 will lie in a common horizontal plane at right angles to the first named vertical plane. It is to be understood that under variations of timing and when different fuels are used the specific relationship of the axes and the crank-arm pivots may be varied without departing from the spirit of the present invention.

The crank-arms 24 which carry the crank-pins 22 are formed with diametrically opposite extensions upon which counterweights 48 are mounted. These counterweights balance the rotating portions of the reciprocating parts of the connecting rods. The crankshaft mass and the arms as a whole balance the reciprocating inertia forces of the engine.

In operation of the present invention it is understood that the engine is constructed and assembled as shown in the drawings. It should be pointed out that due to the fact that the crank-shaft is in effect a plurality of separate units individually functioning while being in constant driving connection with a common power output shaft, the present engine does not require complicated synchronized control mechanism for the performance of the individual engine units since this is attained by reason of the relationship of the concentric and eccentric crankshaft axes to each other and their articulate supports, and also by reason of the action obtained by the accumulator plates 33. The operation of the engine here shown can be best understood with reference to Figs. 4 to 9 of the drawings, where engine performance at full throttle is disclosed. In the engine card shown in Fig. 8 it will be seen that ignition takes place at approximately thirty-five degrees from top dead-center, as indicated by the point S, and that the portion of the curve lying along the zero crank angle represents the period when the piston 13 is moving to its top dead-center position, as indicated in Fig. 4 of the drawings. It is to be understood that the solid line on the chart shown in Fig. 8, which extends upwardly from a pressure calibration of 500 to 900 and then along the power curve to approximately 300, represents normal engine performance. With the present invention the performance is indicated by the usual lower curve but from the pressure calibration of 500 to 600 and then returning to 300. Here it will be seen that at a pressure of 500 pounds per square inch the crank turns approximately 15 degrees, during which time the pressure per square inch rises to 600 pounds. It maintains this pressure until the crank has moved to an angle of the order of 50°. During this time the engine parts are in motion from dead-center to approximately 50° while the accumulator plate 33 is deflected, as shown in Fig. 5 of the drawing. It will be understood that when the fuel was ignited at the point S, as marked on the indicator card shown in Fig. 8, and being near the end of the compression cycle, the piston will continue to rise until it reaches top dead-center. Normally, the pressure rises to its peak in a relatively short angular movement of the crankshaft. In the present instance the dead-center load is eliminated as a relatively high pressure, here indicated at 600 pounds, is maintained over approximately 50 degrees of crank-pin travel.

In order to understand the exact operation of an engine embodying the present invention reference should be made at this time to the diagram disclosed in Fig. 9. Here it will be seen that when the piston is on top dead-center, as indicated in Fig. 4 of the drawing, the center lines of the oscillating arms 26 and the radius arms 46 will intersect at right angles to each other, and at the point of intersection the axes of the crank-shaft sections 23^a will occur. The center of the oscillating arms 26 will also lie in the same plane with the center of the engine cylinder. At this time the center of the eccentric crankshaft sections 23^b will be spaced upwardly from the axis of the concentric crankshaft sections 23^a. The axis of the eccentric crankshaft section 23^b is the fixed axis for the crank-pin 22, and when the engine is on top dead-center the crank-pin 22 will of course lie in the same vertical plane as the pivot pin 30 and the intermediate crank axes. It is to be understood that in the normal operation of a four-cycle engine the accumulator plate 33 will

flex only during that portion of the power stroke shown on the indicator card by dotted lines at approximately 600 pounds pressure and the extreme pressures indicated in solid lines from 600 to 900 pounds will be eliminated. The condition of the engine parts at this time is as shown in Fig. 5 of the drawings. When, however, the crank throw moves to an angle of from 50 to 55 degrees on its power stroke the tension strength of the accumulator plate 33 will balance out the force and restore the plate 33 to its normal position of equilibrium. It will be appreciated that during the time the accumulator plate 33 flexes downwardly the crankshaft structure swings vertically on the arc described from the axis of the power output shaft 42, and that when the accumulator plate 33 is restored to equilibrium the crankshaft unit will move upwardly on the arc described from the axis of the power output shaft 42. Furthermore, it should be pointed out that this axis is tangent to the vertical center line of the engine cylinder. On the scavenging cycle of one cylinder the equilibrium of the accumulator plate 33 is not disturbed. At that time the crankshaft and its pins move in the manner specifically shown in Fig. 9 of the drawings, where it will be seen that as the crankshaft moves from dead-center to one-quarter stroke it will rotate around the axis of the eccentric crankshaft section. However, simultaneously therewith the axis of the concentric crankshaft section must also move, and since the axis of the eccentric crankshaft section is confined to horizontal travel along the arc of the oscillating arms 26 and the axis of the concentric crankshaft section is confined to travel vertically along the arc of the radius arm 46 the axis of the eccentric crankshaft section will move to the point X, from its dead-center point W, and at that time the axis of the concentric shaft will move to the point W. Simultaneously therewith the crank pin 22 will move from the point W' to the point X'. As the crank continues to rotate the axis of the eccentric crankshaft will move back along the arc as established by the oscillating arm 26 to the point W, and the axis of the concentric crankshaft will have moved upwardly along the arc defined by the radius arm 46 to the point Y, which will be on dead-center of the cylinder. At this time the crank-pin 22 will have traversed one-half of its revolution and will be at the point Y'. As the crankshaft continues to rotate in the direction of the arrow a, as indicated in Fig. 9, the axis of the concentric crankshaft section 23^a will be compelled to move downwardly along the arc defined by the radius arm 46 while the axis of the eccentric crankshaft section 23^b will move downwardly along the radius of the oscillating arm 26 to the point Z. When the point Z is reached the crank-pin 22 will be at the point Z', and as the crankshaft moves the crank-pin 22 to its original dead-center position at W' the eccentric crankshaft section 23^b will move down along the arc of the radius arm 46 to its original position at W, and the axis of the concentric crankshaft section 23^a will return again to its lowermost position at Y.

The foregoing description traces the orbit of the crankpin 22 when it is on its scavenging stroke. This has been done because it is much simpler to describe the relative movement of the concentric crankshaft sections 23^a and the eccentric crankshaft sections 23^b. It should be pointed out, however, that due to the fact that the pivot shaft 30 carrying the oscillating arms 26 are mounted upon the accumulator plates 33

the impact of explosive force which takes place at approximately the 600-pound calibration on the indicator card, shown in Fig. 8 and which is illustrated in Fig. 5 of the drawing, will cause all of a crankshaft unit 23 to move downwardly bodily on approximately dead-center as controlled by the vertical swinging movement of the radius arm 46. If we assume, by way of example, and with reference to the diagram shown in Fig. 9, that the amount of downward deflection is represented between the points V and W, then the crank-pin 22 will move downwardly more rapidly for a portion of its travel as represented along the 600-pound calibration in Fig. 8. When the crank-pin has traversed approximately 50 degrees the force of the deflected accumulator plate 33 will begin to balance out the force of the explosion in the cylinder, and at approximately the 500-pound calibration on the indicator chart the parts will be restored to the position indicated in Fig. 6 of the drawing, at which time the accumulator plate 33 will again be in equilibrium and will continue to be so throughout the remainder of the power stroke and through the complete scavenging and induction stroke.

In briefly reviewing this operation it will be seen that the fuel is ignited at the point S designated on the indicator chart in Fig. 8, and which is near the conclusion of the compression cycle of the engine. Thus, when the piston is at top dead-center the moment about the crankshaft axis is zero. As the pressure of the burning gases rises sufficiently the piston 13, connecting rod 20, crankshaft 23, and the radius arms 46 move as a unit about the axis of the power output shaft 42. Hence, the distance from the center of the shaft 42 and the center of the crankshaft section 23^a becomes the instantaneous moment arm, and the entire force acting upon the piston 13 will at that time be applied tangent to a circle described by the axis of crankshaft section 23^a as it moves around the axis of the power output shaft 42. When this takes place rotation will be imparted to the power output shaft 42 incident to the movement. By reference to Fig. 6 of the drawing it will be seen that the accumulator plate 33 has returned to its normal unflexed position. This takes place approximately when the crankshaft has rotated 55 degrees beyond top dead-center. When this curve is plotted on the indicator card shown in Fig. 8 it will be observed that the point corresponds to a pressure of the order of 490 pounds per square inch. It will be noted that when the piston is at its top dead-center that one-hundred percent of the explosive force acting thereagainst is applicable as tangential force. This is entirely contrary to the performance of a conventional internal combustion engine, since as shown by solid lines on the indicator chart in Fig. 8 the tangential force for this position is zero.

It will be recognized that due to the relationship of the concentric crank axes to the eccentric crank axes and their floating supports, the crankshaft mass and arms 46 will move in a direction opposite to the piston movement. The product of the mass of the crankshaft and its acceleration will equal the product of the piston reciprocating mass and its acceleration. This insures one-hundred percent balance of the first harmonic phase within the entire cycle of 360 degrees.

If a conventional type crankshaft is used with the accumulator plate mounting it is possible to balance out one-half of the first harmonic phase while obtaining the other novel advantages in operation, as previously explained.

In the foregoing explanation of the present invention all of the conditions described are full throttle conditions or when sufficient resistance to the rotation of the crankshaft is set up to overcome the inherent resistance of the accumulator plate and to force the plate to flex. It will therefore be evident that a high degree of engine efficiency will be obtained when the engine operates at half throttle.

10 It will thus be seen that by the use of an engine of the construction here disclosed and by practising the method of operating the same, a reciprocating type internal combustion engine is provided in which maximum substantially uniform torque is obtained, thus making it possible to produce a smooth running engine, the parts of which will not wear readily, and in the performance of which a high percentage of the explosive force applied to the piston is converted into useful work.

15 It will also be recognized from a study of Fig. 8 of the drawing that the explosive force of the engine is damped during its initial period and takes place under conditions which are not those of the usual high compression type of engine, thereby insuring an engine that runs smoothly and within which maximum engine efficiency is obtained with a minimum wear and vibration of engine parts, and thus a minimum strain thereon.

20 While I have shown the preferred form of my invention and method for practising the same, it is to be understood that various changes might be made in the combination, construction and arrangement of parts, as well as variations in the 25 steps of the method, by those skilled in the art, without departing from the spirit of the invention as claimed.

25 Having thus described my invention, what I claim and desire to secure by Letters Patent is:

30 1. In a reciprocating type internal combustion engine having a cylinder, reciprocating piston, crankshaft, and connecting rod, the method of damping out the maximum explosive force exerted on a piston at top dead-center, which consists in supporting the crankshaft by resilient means having a predetermined resistance value to said explosive force.

35 2. An internal combustion engine comprising a cylinder, a piston reciprocating therein in response to explosive force, a crankshaft unit, a connecting rod between the crankshaft and the piston, a power output shaft parallel to the crankshaft, driving means between the crankshaft and the power output shaft, radius arms connecting the power output shaft and the crankshaft whereby the two shafts are held at a fixed radial length with relation to each other, and the two shafts are separately free to rotate, and resilient means supporting the crankshaft against arcuate movement around the axis of the power output shaft and tending to yieldably resist downward movement of the crankshaft when the explosive force exerted against the piston exceeds a predetermined magnitude.

40 3. An internal combustion engine comprising a cylinder, a piston therein, a crankshaft formed with a crank throw carrying a pin and having concentric and eccentric crankshaft sections, the axes of which are offset with relation to each other and both of which axes lie in a plane common to that of the crank-pin, a power output shaft parallel to the crankshaft, a radius arm pivotally mounted upon the power output shaft and rotatably holding the concentric portion of the 45 crankshaft at its outer end, the arc of the axis

of the concentric crankshaft section being tangent to the longitudinal center line of the cylinder, an oscillating arm rotatably engaging the eccentric shaft section and extending downwardly beneath the crankshaft, a pivot shaft for the lower end of said oscillating arm, said shaft being parallel to the crankshaft and intersecting the longitudinal center line of the cylinder, the radial length of said arm being such as to dispose the axis of the eccentric shaft section above the axis of the concentric shaft section when the piston is on top dead-center, and constantly meshed driving gears, one carried upon the power output shaft and the other carried by the concentric crankshaft section.

4. The structure of claim 3 including a resilient support for said pivot shaft of the oscillating arm whereby the crankshaft unit may move downward bodily around the axis of the power output shaft as controlled by the radius arm until the explosive force within the cylinder is overcome by the inherent resiliency of the resilient supporting means.

5. The structure of claim 3 including a resilient support for said pivot shaft of the oscillating arm

whereby the crankshaft unit may move downward bodily around the axis of the power output shaft as controlled by the radius arm until the explosive force within the cylinder is overcome by the inherent resiliency of the resilient supporting means, and a counterweight carried by the crankshaft and diametrically opposed to the crankpin, said counterweight balancing the rotating portion of the reciprocating parts.

EDWIN JACOBSEN.
